DESIGN.

—o—

LE ROY W. FAIRCHILD.

MATCH BOX.

No. 18,781.

Patented Dec. 4, 1888.

UNITED STATES PATENT OFFICE.

LE ROY W. FAIRCHILD, OF NEW YORK, N. Y.

DESIGN FOR A MATCH-BOX.

SPECIFICATION forming part of Design No. 18,781, dated December 4, 1888.

Application filed November 8, 1888. Serial No. 290,338. Term of patent 3½ years.

To all whom it may concern:

Be it known that I, LE ROY W. FAIRCHILD, of New York, in the county of New York and State of New York, have invented a new Design for Match-Boxes, of which the following is a specification.

This invention consists of a design for a match-box of that class carried in the pocket.

The accompanying photograph represents 10 a face view of the side of the box having my design thereon.

The design consists of the representation 15 of a sail wrapped or rolled up into a bundle and bound around with a halyard or line passing through a pulley-block connected to one corner of the sail, and having the representation of a tiller or rudder-handle laid on the bundle and held in place by the halyard or line where wrapped around the bundle.

The design is formed by raised lines and 20 figures struck up so as to impart to it a bold and rich appearance.

A match-box bearing this design is specially suitable for yachtsmen, as the design itself is composed of the representation of articles 25 used on yachts.

I claim—

The design for a match-box, as herein described and shown.

In witness whereof I hereunto set my hand 30 in the presence of two witnesses.

LE ROY W. FAIRCHILD.

Witnesses:

J. R. CAMPBELL,
VICTOR W. BRUNDAGE.
